UNITED STATES PATENT OFFICE.

DANIEL BACON, OF NEW YORK, N. Y.

ELECTROMAGNETIC GOVERNOR.

No. 818,513.

Specification of Letters Patent.

Patented April 24, 1906.

Application filed April 17, 1905. Serial No. 255,898.

To all whom it may concern:

Be it known that I, DANIEL BACON, a citizen of the United States, and a resident of Brooklyn borough, New York city, and State 5 of New York, have invented certain new and useful Improvements in Electromagnetic Governors, of which the following is a specification.

The object of my invention is to provide a 10 device by means of which the action of a governor in controlling the movements of a valve or gate or other mechanism requiring automatic control is communicated by means of electromagnetism, so that the delays and 15 dangers usually attending the overcoming of weight, friction, and other mechanical resistance are done away with and the action of the governor is thereby rendered more certain and instantaneous.

20 In the accompanying drawing I have shown my device as applied to the stem of a steam-valve for engines; but it is to be understood that it is equally applicable to other kinds of valves, gates, and devices generally in 25 which a rotary, rocking, or vibratory movement is employed to increase or diminish the amount of power which is permitted to reach the operating mechanism which the governor is designed to control.

30 A is the top of the valve-casing, and the valve-stem *a* is extended sufficiently to receive the valve-operating mechanism. This stem is screw-threaded, and motion in one direction closes the valve, while motion in 35 the other direction opens the valve.

B C are electric motors mounted loosely upon the valve-stem *a* and driven continuously in opposite directions by a current from the battery *b* *c*, respectively. The motors 40 are provided with the usual collector-rings *d* *e*, provided with the brushes *f* *g* *h* *i*, and the circuits are always closed during the operation of the device. Both motors therefore are constantly running and ready to perform 45 work whenever required. Each motor is provided with an armature D E, respectively, which revolves with it and carries an electromagnet F G, respectively. These magnets are normally idle or quiescent, simply turning 50 freely with their respective motors around the shaft *a*. Fixed or splined to the shaft *a*, and preferably between the two magnets, is the armature H, which is adapted to be picked up by whichever magnet is energized 55 and caused to rotate with it, thereby turning the shaft *a* in the same direction as the mag-

net which picks it up. Each magnet-armature is provided with a collector-ring *j* *k*, respectively, with the brushes *l* *m* *n* *o*, which are connected by suitable wiring to the respective batteries *c* *b* through the circuit-closer I, which is automatically operated by a governor J.

The governor J is attached to some moving part (not shown) of the engine or other mechanism (not shown) the operation of which is to be controlled or governed. The mechanical operation of the governor therefore is the usual one; but the rising and falling of the balls of the governor under variations of speed of the operating mechanism are utilized to make contact at the circuit-closer I, and thereby close the circuit which energizes the magnet G or that which energizes the magnet F, according to whether the speed of the 75 governor is getting too high or too low. To accomplish this result, I provide a contact-finger *p*, secured to the governor-block *q* and forming a part of both magnet-circuits. The play of this finger is such that when the block 80 *q* rises to such point as may be selected as representing the highest speed desired the finger *p* comes in contact with the upper finger *r* of the circuit-closer I. Thereby it serves not only as a stop but to close the circuit through the wires *w* *w'* through the magnet G and the battery *b*. The shaft is thereby at once picked up by said magnet G and turned to close the valve, and thereby diminish the quantity of steam or other power supplied to the operating mechanism. As soon 90 as the speed of the governor thereby becomes reduced, so as no longer to hold the block *q* and finger *p* in their highest position, the balls depress the finger and break the circuit, 95 whereupon the magnet G releases the armature H and the valve then remains stationary.

Should the speed of the governor fall below the point selected for the minimum speed of 100 the operating mechanism, the finger *p* comes against the lower contact-point *s* of the circuit-closer I, and thereby closes the circuit through the wires *y* *y'*, battery *c*, and electromagnet F, which picks up the armature H, 105 and thereby turns the valve-stem *a* to open the valve and let on more power. As soon as the speed of the governor increases enough to lift the finger *p* away from the contact-stop *s* the circuit is broken and the valve becomes 110 stationary in its new position.

The contact-stops *r* *s* are made adjustable

along the circuit-closer I, so that the exact limits at which the governor is made to close the circuit to operate the valve-stem can be made to correspond with various maximum and minimum speeds, as may be required by the various machinery to which the governor is applied.

I claim—

An electromagnetic governor which consists of a governing device adapted to move at a speed corresponding to that of the apparatus to be governed, a circuit-closer adapted to be operated by said governing device upon reaching a predetermined point of high or low speed, an electromagnetic device mount-

ed upon the controlling-stem of the apparatus to be governed, and adapted to turn said stem in either direction as may be required to increase or diminish the speed of said apparatus, and means, substantially as described, whereby an electric current is directed into said electromagnetic device in one or the other direction by the action of said governing device in contacting with said circuit-closer. 20

DANIEL BACON.
